UNITED STATES PATENT OFFICE.

FREDERICK TAYLOR, OF LOWELL, MASSACHUSETTS.

COAT AND HAT HOOK.

SPECIFICATION forming part of Letters Patent No. 374,015, dated November 29, 1887.

Application filed February 1, 1886. Serial No. 190,450. (No model.)

To all whom it may concern:

Be it known that I, FREDERICK TAYLOR, a citizen of the United States, residing at Lowell, in the county of Middlesex and Commonwealth of Massachusetts, have invented a certain new and useful Improvement in Coat and Hat Hooks, of which the following is a specification.

My invention relates to hat and coat hooks, consisting of a wire bent to form a coat or clothes hook and a hat-hook, said hooks being connected by a brace and secured, substantially as hereinafter described, to a laterally-projecting plate.

15 In the accompanying drawings, Figures 1, 3, and 4 are isometric views of hooks constructed according to my improvement, each figure being slightly modified from the others; Fig. 2, a vertical longitudinal section of the 20 attaching-plate, through the center of the same, on the line $x-x$ in Fig. 1, the hooks proper being broken away.

The plate A is of sheet metal, best formed by punching the same out of a larger sheet. 25 The plate A has attaching-eyes a a punched in it, through which wood-screws are driven into the object to which the hook is to be attached. Open eyes B B' are formed at the bottom, as shown in Figs. 1 and 3, or at the 30 top and bottom, as shown in Figs. 3 and 4, to serve as means of attaching the wire portion of the hook to the plate. The eyes B B' are formed in ears projecting from the top and bottom of said plate, and bent at right angles 35 to said plate, each eye being open or formed in two parts, b b', the opening of the eye being at the end of said ear farthest from said plate proper.

The wire part of the hook consists of a hat-hook, a horizontal arm, E, attached to the plate, as hereinafter described, a coat-hook, C, and an S-shaped brace connecting said hat-hook with said coat-hook.

In all the figures the wire is continued up 45 vertically from the coat-hook C, through the lower eye, B', of the plate A, and is then bent backward into or through the plate A, the open eye B being closed around the vertical back, as shown in all the figures.

50 In Figs. 1, 2, and 3 the backward extension d of the back D serves no other purpose than to prevent said back D from rising or turning in the lower open eye, B; but in Fig. 4 said backward extension is carried entirely through

the plate at d', and is screw-threaded to form 55 an attaching-point by which the hook may be secured to a cleat or wall.

In Figs. 1, 2, and 3 an attaching-point, d', which serves the same purpose as the attaching-point d', above described, is formed on the 60 rear end of the horizontal arm E, which, in said last-named figures, is represented as projecting through the plate A.

In Figs. 1 and 2 the attaching-point d' is represented as being a continuation in a straight 65 line of the horizontal arm E; but in Fig. 3 the attaching-point is parallel to the arm E; but this arm E is offset at O, the offset portion being at right angles with said arm and with the attaching-point and resting against the 70 face of the plate A, and being held against said plate by the upper open eye, B, the parts of which are each bent against the front of said offset from opposite sides thereof. In Fig. 4 the arm E is also offset, just as in Fig. 75 3; but the part of the wire in the rear of the offset does not project on the back side of the plate A, and does not therefore serve as an attaching-point.

The construction above described prevents 80 the wire portion of the hook from moving either laterally or vertically on the wall-plate A, and also prevents said wire portion from being accidentally detached from said plate, and the plate, when properly secured, prevents 85 the hook, as a whole, from moving on the object to which it is attached.

I claim as my invention—

The combination of a plate provided with one or more attaching-eyes and with holes to 90 admit the ends of the wire named below, and provided also with one or more ears bent at about right angles to said plate, said ears being provided with eyes open at the ends of said ears, and a wire bent to form hooks, and a 95 brace connecting said hooks, one end of said wire being passed through one of said ears and bent into a hole in said plate, and the other end of said wire being passed through another hole in said plate and screw-threaded 100 in the rear of said plate to form an attaching-point for said hook, as and for the purpose specified.

FREDERICK TAYLOR.
